ELECTRIC COOKING STOVE

Donald A. Smith, Wheaton, Ill., assignor to General Electric Company, a corporation of New York

Application February 26, 1959, Serial No. 54,750

Term of patent 3½ years

(Cl. D81—4)

Fig. 1.

Fig. 2.

Fig. 1 is a perspective view of the front and one side of an electric cooking stove embodying my new design with the covers of the grille element in open position. The side not shown is a mirror image of the side shown.

Fig. 2 is a cross section on line 2—2 of Fig. 1 in the direction of the arrows.

The dominant features of the design reside in the portions shown in full lines.

I claim:

The ornamental design for an electric cooking stove, substantially as shown and described.
